UNITED STATES PATENT OFFICE.

FRANK MAJEWSKI, OF KENSINGTON, ILLINOIS.

DETACHABLE ICE-CREEPER.

1,145,384.

Specification of Letters Patent.

Patented July 6, 1915.

Application filed March 13, 1915. Serial No. 14,137.

To all whom it may concern:

Be it known that I, FRANK MAJEWSKI, a subject of the Emperor of Austria-Hungary, residing at Kensington, in the county of Cook and State of Illinois, have invented certain new and useful Improvements in Detachable Ice-Creepers, of which the following is a specification.

This invention relates to new and useful improvements in a detachable ice creeper.

The main object of the present invention is the provision of an ice creeper having a calked member readily detachable from a base frame which is adapted to be clamped to the heel of a shoe and whereby the ground engaging surface of the heel may be supplied with or freed from the non-slipping device at will.

A still further object is to provide an ice creeper mount which is rigidly clamped to the shoe heel without injuring the heel and is adapted to remain in position thereon during the entire season that the creeper may be desired for use, while a calked creeper plate may be readily sprung into interlocking engagement therewith and instantly and easily removed therefrom at will.

With these general objects in view and others that will appear as the nature of the invention is better understood, the same consists in the novel combination and arrangement of parts hereinafter fully described, illustrated in the accompanying drawings and pointed out in the appended claim.

In the drawings forming a part of this application and in which like designating characters refer to corresponding parts throughout the several views:—Figure 1 is a side elevation of a heel provided with the present invention, a portion of the latter being broken away. Fig. 2 is a perspective view of the creeper mount detached from the heel and partially broken away, the clamping screw being removed therefrom. Fig. 3 is a perspective view of the calked plate detached from the mount, and Fig. 4 is a detail sectional view taken upon line IV—IV of Fig. 3.

Referring more in detail to the drawings, the present invention is illustrated in Fig. 1 as assembled upon the heel 10 of the shoe 11 and the device broadly consists in securing to the heel, the mount shown in Fig. 2

and in providing the calk plate of Fig. 3 which is sprung into and out of position upon the said mount at the will of the wearer.

The creeper mount consists of an arch-shaped metallic band 12, slightly flexible and having its two ends 13 and 14 drawn inwardly and bent into terminal lugs 15 arranged in parallelism. The lug 15 is provided with a perforation 16 therethrough and adapted to freely receive a clamping screw 17, which screw is adapted for threaded engagement with the threaded perforation 18 of the lug 15.

The arch band 12 is provided with projecting hooks 19 here illustrated as three in number and extending in the same directions while a lining 20 is provided for the arch band 12. The mount so formed is readily clamped to the shoe heel 10 by fitting the arch band 12 thereover and to the shape of which it substantially conforms and in then tightening the clamp screw 17 for retaining the arch band rigidly mounted upon the heel, it being noted that the hooks 19 engage over the edge of the shoe sole 21 as best illustrated in Fig. 1 and slightly project between the sole and upper of the shoe.

The calk plate comprises a substantially horse shoe plate 22 having projecting pointed conical calks 23 extending from one face thereof and provided with a cushioning lining 24 upon its opposite face. A plurality of arms 25 herein illustrated as three in number are carried by the plate 22 and extend in the same general direction and are provided with openings 26. The arch band 12 is provided on its outer face with projecting lugs or pins 27 equal in number to the arms 25 and correspondingly spaced apart, the said arms 25 being formed of slightly flexible material, the arm openings 26 are adapted to be engaged over the mount lugs 27 by a slight springing action of the said arms and thus seating the calk plate firmly upon the ground engaging face 28 of the heel. The arm 25 at the rear of the plate has the upper end thereof 29 slightly bent outwardly and it is designed to first engage the forward arms 25 with the corresponding lugs 27 and then easily spring the rear arm over the rear lug 27. The calk plate being readily positioned upon the mount in this manner, it will be apparent that the same

may as readily be removed therefrom by slightly springing the arms 25 outwardly of the arch band and thus disengaging the arm openings 26 from the band lugs 27. It 5 will be understood that the mount is to be constantly worn upon the shoe heel being clamped thereon in the manner above described and the same will in no manner inconvenience the wearer of the shoe, while 10 the mount thus provides a ready means for positioning the creeper plate in its operative position upon the heel and so that the same may be readily detached at will, thus providing a strong and serviceable ice creeper, 15 the calk plate being of convenient size to be carried in the pocket.

While the form of the invention herein shown and described is what is believed to be the preferred embodiment thereof, it is 20 nevertheless to be understood that minor changes may be made in the form, proportion and details of construction without departing from the spirit and scope of the invention as set forth in the appended claims.

What I claim as new is:—

A device of the class described comprising a heel encircling flexible band having indrawn ends, a clamping screw operatively connected between the said band ends, heel engaging hooks projecting from one edge 20 of the said band, a lining carried by the said band, outwardly projecting spaced lugs upon said band, a horse shoe shaped plate, sharpened calks projecting from one face of the said plate, a cushioned lining secured 35 to the face of the said plate opposite the said calks and spring arms carried by the said plate and extending in an opposite direction from the said calks and having openings therethrough detachably positioned over the said lugs when the device is assembled.

In testimony whereof I affix my signature in presence of two witnesses.

FRANK MAJEWSKI.
